CLAIM

The ornamental design for a “tailgate extender,” as shown and described.

DESCRIPTION

FIG. 1 is a right side, elevation view showing my design for a tailgate extender;

FIG. 2 is a right side, perspective view thereof;

FIG. 3 is a left side, perspective view thereof;

FIG. 4 is a left side, elevational view thereof;

FIG. 5 is a rear view thereof;

FIG. 6 is a top view thereof;

FIG. 7 front view thereof;

FIG. 8 is a right side, perspective view thereof, as viewed from underneath;

FIG. 9 is left side, perspective view thereof, as viewed from underneath, which also shows two tailgate sidewall extension panels in phantom; and,

FIG. 10 is a bottom view thereof, which also shows two tailgate extension panels in phantom.
